UNITED STATES PATENT OFFICE.

YASUTARO KATSUMOTO, OF NISHI-KU, OSAKA, JAPAN.

CORE OF TRANSFORMERS.

Application filed February 21, 1922. Serial No. 538,394.

To all whom it may concern:

Be it known that I, YASUTARO KATSUMOTO, a subject of the Emperor of Japan, residing at No. 36, Torishima-cho, Nishi-ku, Osaka, Japan, have invented new and useful Improvements in a Core of Transformers, of which the following is a specification.

This invention relates to improvements in transformer cores having radially extending frames made of sheet iron, and has for its object to provide a transformer having a large cooling surface, while at the same time the quantity of iron and copper used in constructing the core is comparatively small.

In the accompanying drawings a number of examples of cores constructed in accordance with the present invention are shown, and from which the principle of the invention will be readily understood. In said drawings:

Fig. 1 is a perspective view of a transformer provided with a core having twelve frames;

Fig. 2 is a plan view of the transformer shown in Fig. 1;

Figs. 3 and 4 are plan views of transformers having fifteen and eighteen frames respectively;

Figs. 5 and 7 are sectional plan views of the assembled inner legs of the frames forming the central pole of the core of the transformers shown in Figs. 2 and 4 respectively;

Fig. 6 is a sectional plan view illustrating another form of central pole.

The same characters of reference designate the same parts in the different figures of the drawings.

Referring to the drawings, each of the frames comprises an inner vertical leg *a*, an outer vertical leg *b*, and horizontal legs *c* connecting the legs *a* and *b* at the upper and lower ends thereof, said legs together forming a tetragonal frame. The outer and connecting legs of the sections of the frame may be of any convenient form, provided they are of the same area, but the inner legs are of rhombic formation.

The frames above described are arranged radially, the inner legs being assembled side by side to form the central pole of the core, as clearly shown in the drawings. The assembled inner legs may be disposed in a single layer, or in two or more layers, according to the number of frames. The sec-

tion of the pole thus formed is a regular hexagon. The frames may be so assembled that the inner legs form an opening at the center of the core, as shown in Fig. 6, or if preferred, the center portion may be solid, as shown in Fig. 7. In Figs. 2 and 3, the assembled legs form an opening at the center, but said opening is filled with a sheet iron core *e*. The connecting legs *c* may extend straight as shown in Fig. 2, but all, or some of them may be curved along their sides as shown in Figs. 3 and 4, when desired. The connecting legs attached to the inner layer of the central pole are disposed outside of those attached to the outer layer of said pole, but all of the outer vertical legs *b* are distributed at the same distance from the center, that is to say, in a circle.

Coils *d* are wound on the central pole of the core, as is well known in transformers having radial cores.

In the present invention, a sectional view of the central pole of the core is a regular polygon, and the outer legs are divided into a number of sections distributed almost all over the outer surface of the coils, and the laminations of iron comprising a single unit of the frame are of the same dimensions. Consequently, the mean length of the connecting legs is reduced, and that of the inner legs may also be reduced. Because of this construction the core can be divided into a number of sections so that said core may readily be distributed almost over the entire outer surface of the coils. As a result of this disposition, the thickness of the outer legs may be greatly reduced while keeping the required sectional area, thus effecting a considerable saving in the quantity of iron used in the construction of the transformer.

Furthermore, as the cross section of the assembled inner legs is a regular polygon, the coils may be wound thereon so as to form a circle, so that the mean length of the coils may be reduced. This saves a considerable quantity of copper in the total length of the coils. Moreover, the curvature of the coils being less sharp, not only is the operation of winding rendered very easy, but the insulation is not subject to injury by any necessity for sharply bending the wire.

From the foregoing it will be seen that the external surface of the core is very

large compared with its volume, which affords effective cooling of the transformer, thus considerably increasing the efficiency of the latter, while the weight, as well as the initial cost, are materially reduced.

Having thus described my invention, what I claim is:

1. A transformer core, comprising a plurality of radially extending sheet iron frames of uniform dimensions, each having an inner vertical leg, an outer vertical leg, and a pair of horizontal legs connecting the ends of said vertical legs, the inner legs of the frames being disposed in contiguous relation in at least two layers and forming a central pole, the sectional form of the inner legs being rhombic and the outer vertical legs disposed in a circle.
2. A transformer core, comprising radially extending sheet iron frames of uniform dimensions, each having an inner vertical leg, an outer vertical leg, and a pair of horizontal legs connecting the ends of said ver-

tical legs, the inner legs of the frames being disposed in contiguous relation in at least two layers and forming a central pole of hexagonal section, the sectional form of the inner legs being rhombic and the outer vertical legs disposed in a circle.

3. A transformer core, comprising radially extending sheet iron frames of uniform dimensions, each having an inner vertical leg, an outer vertical leg and a pair of horizontal legs connecting the ends of said vertical legs, said connecting legs being curved along their sides, the inner legs of the frames being disposed in contiguous relation in at least two layers and forming a central pole of hexagonal section, the sectional form of the inner legs being rhombic and the outer vertical legs disposed in a circle.

In testimony whereof I have signed my name to this specification.

YASUTARO KATSUMOTO.
